US00D755726S

(12) **United States Design Patent**
Michas

(10) **Patent No.:** **US D755,726 S**
(45) **Date of Patent:** **** May 10, 2016**

(54) **CABLE REEL FOR RETRACTABLE BOOSTER CABLES**

(71) Applicant: **DELK RESOURCES, INC.**, Nashville, TN (US)

(72) Inventor: **Luke W. Michas**, Hendersonville, TN (US)

(73) Assignee: **Delk Resources, Inc.**, Nashville, TN (US)

(**) Term: **14 Years**

(21) Appl. No.: **29/508,943**

(22) Filed: **Nov. 12, 2014**

(51) LOC (10) Cl. **13-03**

(52) U.S. Cl. **USPC D13/153**

(58) **Field of Classification Search**

USPC D13/139.1-139.8, 153, 120, 137.4, 110, D13/155; D8/358, 359, 356; 242/376, 242/405.3, 379.2; 137/15.18

CPC .. B65H 75/4434; B65H 75/406; B65H 75/40; B65H 75/446; B65H 75/38

(57) **CLAIM**

The ornamental design for a cable reel for retractable booster cables, as shown and described.

DESCRIPTION

FIG. 1 is a top perspective view of cable reel for retractable booster cables showing my new design.

FIG. 2 is a bottom perspective view thereof.

FIG. 3 is a front elevational view thereof.

FIG. 4 is a right side elevational view thereof.

FIG. 5 is a left side elevational view thereof.

FIG. 6 is a rear elevational view thereof.

FIG. 7 is a top plan view thereof; and,

FIG. 8 is a bottom plan view thereof.

In the drawings, the broken lines are for the purpose of illustrating environment only and form no part of the claimed design.

1 Claim, 8 Drawing Sheets
